(57) **CLAIM**

The ornamental design for a wheel, as shown and described.

DESCRIPTION

FIG. 1 is a front left perspective view of a wheel showing my new design;

FIG. 2 is a rear left perspective view of the design shown in FIG. 1;

FIG. 3 is a rear right perspective view of the design shown in FIG. 1;

FIG. 4 is a front right perspective view of the design shown in FIG. 1;

FIG. 5 is a left side view of the design shown in FIG. 1;
FIG. 6 is a right side view of the design shown in FIG. 1;
FIG. 7 is a rear view of the design shown in FIG. 1;
FIG. 8 is a front view of the design shown in FIG. 1;
FIG. 9 is a top view of the design shown in FIG. 1; and,
FIG. 10 is a bottom view of the design shown in FIG. 1.
The broken lines shown in the figures are included for the purpose of illustrating portions of the wheel and form no part of the claimed design.**1 Claim, 10 Drawing Sheets**FIG. 1

FIG. 2

FIG. 3

FIG. 4

FIG. 5

FIG. 6

FIG. 7

FIG. 8

FIG. 9

FIG. 10
